Primary Examiner — Cynthia Ramirez

(74) Attorney, Agent, or Firm — Taylor English Duma LLP

(57) CLAIM

We claim the ornamental design for a lawn refuse bag insert, as shown and described.

DESCRIPTION

FIG. 1 is a top perspective view of an aspect of the lawn refuse bag insert in an assembled configuration.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a top plan view of the lawn refuse bag insert of FIG. 1 in a blank configuration.

The broken lines in the figures shown portions of the lawn refuse bag insert, which form no part of the claimed design.

1 Claim, 6 Drawing Sheets
